[57] CLAIM

The ornamental design for a condiment bottle refilling container, as shown and described.

DESCRIPTION

FIG. 1 is a perspective view of a condiment bottle refilling container showing my new design;

FIG. 2 is a front elevational view thereof; the rear elevational view being a mirror image thereof;

FIG. 3 is a left side elevational view thereof; the right side elevational view being a mirror image thereof;

FIG. 4 is a top plan view thereof; and,

FIG. 5 is a bottom plan view thereof.

FIG.1.

FIG. 3.

FIG. 2.

FIG. 5.

FIG. 4.
